G. HAZARVARTIAN.

PROJECTING DEVICE.

APPLICATION FILED FEB. 3, 1917.

1,311,694.

Patented July 29, 1919.

UNITED STATES PATENT OFFICE.

GARABED HAZARVARTIAN, OF BROOKLYN, NEW YORK.

PROJECTING DEVICE.

1,311,694.

Specification of Letters Patent.

Patented July 29, 1919.

Application filed February 3, 1917. Serial No. 146,472.

To all whom it may concern:

Be it known that I, GARABED HAZARVARTIAN, a subject of the Sultan of Turkey, residing at Brooklyn, in the county of Kings 5 and State of New York, have invented certain new and useful Improvements in Projecting Devices, of which the following is a specification.

This invention has relation to projecting devices, with special reference to ordnance, and has for an object to provide a device operable upon the catapult principle for throwing or projecting hand grenades, bombs or the like.

15 Another object of the invention is to provide a device of this character, including a rotatably mounted element adapted to support the articles to be projected whereby the element may be rotated, with means for 20 automatically releasing the objects at a predetermined point during the revolution of the element, whereby the object may be projected to a great distance by centrifugal force.

25 In addition to the foregoing my invention comprehends improvements in the details of construction and arrangement of parts to be hereinafter more fully described and particularly set forth in the appended 30 claims.

In the accompanying drawings in which similar and corresponding parts are designated by the same characters of reference, throughout the several views in which they 35 appear:

Figure 1, is a view in side elevation of a projecting device constructed after the manner of my invention, and illustrating in dotted lines the position of the rotatable element just prior to the release of the object.

Fig. 2, is a view of the device in front elevation, and

Fig. 3, is a detail section taken on the line 3—3 of Fig. 2.

45 With reference to the drawings 10 indicates a pair of vertical, horizontally spaced standards mounted upon a base plate 11, said standards supporting at their upper ends a horizontal shaft 12. The ends of the 50 shaft 12 are reduced as at 13 to enter sleeves 14 which are journaled in the standards, the inner ends of the sleeves 14 being spaced from the enlarged portion of the shaft 12 whereby to form in effect a pair of annular 55 grooves 15.

A pair of arms 16 are provided, having

their intermediate portions apertured whereby to receive in said apertures the reduced portion 13 of the shaft 12, the arms being thus disposed in the annular grooves 15 as 60 will be evidenced upon reference to Fig. 2 of the drawings.

The arms 16 are fixed to the shaft for rotation therewith, and a pulley 17 is fixedly secured to one of the sleeves 14, 65 while a pulley 18 is located below the pulley 17 in vertical alinement therewith, said pulley being mounted upon a transversely extending shaft 19 journaled in the standards 10, and a belt 20 passes over 70 both pulleys for transmitting motion to the uppermost pulley from the lowermost. A source of power 21, which may be an electric motor, internal combustion engine, or the like, is mounted upon the base plate 10 75 and the power shaft 22 thereof is provided with a spur wheel 23 adapted for meshing engagement with a spur wheel 24 mounted upon the projecting end of the shaft 19.

While the arms 16 are fixed to the shaft 80 12 for rotation therewith, they are adapted for slight oscillatory movement toward and away from each other, and adjacent ends of the arms are provided with pins 25 extending toward each other for the purpose 85 of entering recesses 26 in a hand grenade, bomb or the like 27, which is to be projected. The recesses are provided at opposite sides of the object, and the pins normally enter the recesses to support the object 90 in a releasable manner. The arms at their ends opposite from that which support the bomb are provided with counterweights 29 whereby to balance the arms when a bomb is supported thereby to permit uniform 95 rotation of the arms.

Said mentioned ends of the arms bearing the counterweights 29 are formed with apertures 30, in transverse alinement for supporting the cylindrical ends 31 of a trigger bar 32 which is rectangular, and flattened in cross section and is designed for rotative movement. One of the reduced ends 31 of the trigger bar carries a trip 33 which is substantially triangular in configuration with one curved edge 34, and is fixed to the trigger bar for rotation therewith. Each arm 16 is provided on its inner face adjacent the trigger bar with a lug 35 and when an object is supported between the opposite ends of the arms, the rectangular portion 32 of the trigger bar is disposed as 100 105 110

illustrated in Fig. 3, whereby the lugs 35 are engaged by the ends of the rectangular portion of the trigger bar to urge the ends of the arms 16 supporting said trigger bar, 5 in separated relation, so as to retain the opposite ends of the arms in a position to retain the pins 25 in engagement in the recesses of the object to be projected. A coil spring 36 is disposed between the ends of 10 the arms bearing the trigger bar, with the ends of the spring connected to each arm whereby to normally urge said ends of the arms toward each other in opposition to the resistance offered by the engagement of 15 the trigger bar with the lugs 35.

Located upon the base plate 11 is a trip bar 36 movable vertically in guides 37 whereby the trip bar may be moved into a position in the path of movement of the 20 trip arm 33 mentioned above. A lever 38 is fulcrumed at an intermediate point as indicated at 39, and one end of the lever is adapted to engage a recess formed in the lower end of the trip bar 36, while the opposite end of the lever is connected to a flexible element 40 which passes around a pulley 41 mounted upon the base plate, said flexible element extending to a safe distance from the device whereby the trip bar 36 25 may be raised to discharge the device in a manner which will be presently obvious.

A bomb or the like is supported between the arms as indicated in the drawings, and while the trip bar 36 is in a lowered position, the motor 21 is energized whereby its 35 rotative movement is communicated to the shaft 19, and from thence through the medium of the belt and pulleys to the upper shaft 12 whereby to impart to the arms 16 40 rotation at a comparatively high rate of speed. When the speed of rotation of the arm has reached the limit required to project the object to the distance desired, the flexible element 40 is drawn to raise the opposite end of the lever 38 to which the flexible element is connected thereby raising the trip bar 36 into engagement with the trip arm 33 mounted on the arms of the device. When the trip arm 33 is engaged it 45 will be partially rotated so as to correspondingly rotate the trigger bar to disengage the ends of the rectangular portion 32 thereof from the lugs 35 whereby the spring 36 may draw said ends of the arms 16 toward 50 each other to correspondingly separate the opposite ends of the arms whereby to withdraw the pins 25 from engagement with the object 27, the centrifugal force accumulated by the rotating arms being sufficient to im- 55 part to the object an impetus to throw the same to a great distance. It will be obvious that if the trip bar 36 is properly arranged the object will be released so as to describe the proper trajectory to throw the object 60 65 to the distance desired.

Thus it will be seen, that I have provided a novel projecting device for hand grenades, bombs or the like, which is extremely simple in operation and construction thereby reducing the possibility of the device getting out 70 of order during operation thereof, as is frequently the case in devices of this character of a more complicated design.

While I have illustrated and described my invention with some degree of particularity, I realize that in practice that various alterations thereover may be made, and I therefore desire to reserve the right and privilege of changing the form of the details of construction, or otherwise altering 75 80 the arrangement of the parts without departing from the spirit of the invention or the scope of the appended claims.

Having thus described my invention what I claim as new and desire to secure by Letters Patent is;

1. In a projectile impelling device, a rotatable element including a pair of relatively movable members adapted to support the projectile upon and therebetween, resilient 90 means for urging the members out of such engagement, and a trigger mechanism for retaining the members in such engagement, and means operable during rotation of the elements to release the trigger mechanism to 95 permit the projectile to be impelled.

2. In an object projecting device, a pair of arms mounted for rotation and for movement toward and away from each other, means on said arms for supporting an object 100 therebetween when said arms are brought together, means for rotating the arms, means for retaining the arms in position to support the object, and means operable during rotation of the arms to cause the arms to be separated whereby to release the object to project the same from the device by centrifugal force.

3. In an object projecting device, a pair of arms mounted for rotation, adjacent ends of said arms being adapted to support therebetween the object, means for retaining said arms in engagement with the object, means for rotating the arms, and means operable during the rotation of the arms for moving the same to disengage the arms from the object whereby to project the same from the device by centrifugal force.

4. In an object projecting device, a pair of arms mounted for rotation and disposed in parallelism, means for supporting between the arms at one end thereof the object to be projected, means disposed at the opposite ends of the arms for retaining the same in separated relation whereby to retain the opposite ends of the arms in engagement with the object, means for rotating the arms, and means operable during rotation of the arms to cause the means for retaining the arms in separated relation to be released, whereby 125 130

the opposite ends of the arms may be separated to release the object and cause the object to be projected from the machine by centrifugal force.

- 5 5. In an object projecting device, a pair of spaced parallel arms mounted for rotation, means for rotating the same, said arms being movable toward and away from each other, to support therebetween at one of
10 their ends an object to be projected, a trigger bar mounted at the opposite end of the arm for releasably retaining the same in spaced relation, resilient means for urging said ends of the arms bearing the trigger
15 arm, toward each other in opposition to the

trigger bar, and a stationarily mounted trip for engaging said trigger bar during rotation of the arms to actuate the same whereby to permit the ends of the arms bearing the trigger bar to be moved toward each other whereby to separate the opposite ends of the arms to release the object, whereby to project the same from the device by centrifugal force.

20 In testimony whereof I affix my signature 25 in presence of two witnesses.

GARABED HAZARVARTIAN.
